FIG. 1.

FIG. 2.

INVENTOR:

Howard B. Rand
by night Brown County May.

ATTY'S-

UNITED STATES PATENT OFFICE.

HOWARD B. RAND, OF MERRIMAC, MASSACHUSETTS.

LAMP-SOCKET GUIDE FOR HEADLIGHTS.

1,276,415.

Specification of Letters Patent.

Patented Aug. 20, 1918.

Application filed November 4, 1916. Serial No. 129,488.

To all whom it may concern:

Be it known that I, HOWARD B. RAND, a citizen of the United States, residing at Merrimac, in the county of Essex and State 5 of Massachusetts, have invented new and useful Improvements in Lamp-Socket Guides for Headlights, of which the following is a specification.

This invention relates to automobile and 10 other headlights in which the source of illumination is an incandescent electric lamp, the tubular socket of which is longitudinally adjustable in a tubular guide attached to the headlight casing and projecting backwardly therefrom, said guide being coaxial with the headlight reflector and permitting the longitudinal adjustment of the socket and lamp to focus the latter to vary its distance from the reflector, the latter being 15 usually parabolic.

The object of the invention is to provide frictional confining means adapted to hold the socket with sufficient firmness at any desired adjustment, and at the same time to yield to a predetermined force exerted on the socket for the purpose of adjusting the same.

The invention is embodied in the improvements which I will now proceed to describe and claim.

Of the accompanying drawings forming a part of this specification,—

Figure 1 represents a side view of a lamp socket guide, a headlight casing to which the guide is attached, and portions of a lamp socket and an electric lamp carried thereby.

Fig. 2 represents an enlarged section on the line 2—2 of Fig. 1.

The same reference characters indicate 0 the same parts in all of the figures.

In the drawings,—

12 represents the casing of a headlight and 13 a tubular guide attached to the center of the casing and projecting rearwardly therefrom; the guide being open at both ends and communicating with a central opening in the casing and in its reflector. 14 represents a tubular lamp socket carrying an incandescent electric lamp and movable longitudinally in the guide 13 to adjust the lamp relatively to the reflector of the headlight.

In carrying out my invention, I provide the guide 13 with a frictional retaining means adapted to exert a radial inward

yielding pressure on the periphery of the lamp socket 14 and thus retain the socket by friction at various adjustments, said retaining means exerting sufficient pressure to prevent accidental movement of the socket 60 in any direction and being adapted to yield to a predetermined force exerted on the socket and permit a longitudinal movement of the socket in either direction.

I have here shown the said retaining 65 means embodied in a shoe 15 formed to conform to a portion of the periphery of the socket 14, and means for pressing said shoe radially inward against the socket.

The shoe is preferably one end portion of 70 a strip of tempered resilient steel. The opposite end portion of said strip is formed as a jaw 16 adapted to bear on a portion of the periphery of the guide 13, as shown by Fig. 2. The said jaw and guide are connected 75 by a resilient arched portion 17, which arched portion forms a handle whereby the retaining means may be moved circumferentially with relation to the guide or may be removed entirely therefrom and replaced 80 on the same.

The guide 13 is provided with an opening 18 formed to expose a portion of the periphery of the socket 14, and to receive the shoe 15, so that said shoe is adapted to spring 85 into the guide and bear yieldingly on the exposed portion of the socket.

When the strip, including the shoe, the jaw and the connecting neck, is removed from the guide 13, the shoe and jaw spring 90 inwardly toward each other. It follows therefore that, when the said strip is engaged with the guide as shown, it is put under tension so that the shoe is pressed strongly inward.

I have found that, by the use of the frictional retaining means above described, the socket may be held with sufficient firmness at any desired longitudinal adjustment and may be adjusted by the application of sufficient force to overcome the frictional hold 100 of the shoe on the socket.

The resilient strip may be partially rotated on the guide, as indicated by dotted lines in Fig. 2, to withdraw the shoe from 105 the opening 18, thus permitting the socket to be inserted without obstruction by the shoe which projects into the guide through the opening 18 when there is no socket in the guide.

I claim:—

The combination with a lamp-socket holder having a lateral opening, of a retaining member mounted on said holder and having a portion arranged to project through said opening to engage frictionally a lamp socket within said holder, said re-

taining member having a handle portion whereby it may be oscillated about said holder into and out of socket-engaging 10 position.

In testimony whereof I have affixed my signature.

HOWARD B. RAND.
